(57) **CLAIM**

The ornamental design for a portable sawhorse, as shown
and described.

DESCRIPTION

FIG. 1 is a front elevation view of a portable sawhorse
showing our new design.

FIG. 2 is a left side elevation view thereof.

FIG. 3 is a top plan view thereof.

FIG. 4 is a bottom plan view thereof.

FIG. 5 is a perspective view thereof.

FIG. 6 is another perspective view thereof.

FIG. 7 is another perspective view thereof.

FIG. 8 is a perspective view of the design in a folded state.

FIG. 9 is the bottom plan view indicating an enlarged view
area shown in FIG. 10.

FIG. 10 is an enlarged view of the circled area in FIG. 9.

FIG. 11 is a perspective view indicating an enlarged view
area shown in FIG. 12.

FIG. 12 is an enlarged view of the circled area in FIG. 11.

FIG. 13 is another perspective view indicating an enlarged
view area shown in FIG. 14; and,

FIG. 14 is an enlarged view of the circled area in FIG. 13.
